UNITED STATES PATENT OFFICE.

GEORGE HEAP, OF CLEVELAND, OHIO.

SAFETY DEVICE FOR MACHINES.

1,116,061.

Specification of Letters Patent. Patented Nov. 3, 1914.

Application filed August 8, 1913. Serial No. 733,727.

To all whom it may concern:

Be it known that I, GEORGE HEAP, a subject of the King of Great Britain and Ireland, residing at Cleveland, in the county 5 of Cuyahoga and State of Ohio, have invented a certain new and useful Improvement in Safety Devices for Machines, of which the following is a full, clear, and exact description, reference being had to 10 the accompanying drawings.

This invention is for a safety device to be used in connection with machines which are dangerous to the hands of the operator because the article to be acted upon must be 15 held by the hands near to mechanism in which they are liable to be injured.

The principal object is to prevent running the machine while the operator's hands are too near the danger zone. This is accomplished by providing a pair of latches which prevent the shifting of a clutch into driving position, except when each hand is resting on controlling mechanism, insuring them being out of the danger zone when the 25 machine is started.

As shown in the accompanying drawings, my device is applied to a press for setting the ends on pasteboard boxes.

This invention is hereinafter more fully 30 described and the essential characteristics are set forth in the claims.

In the drawings, Figure 1 is a front elevation of an end setting machine showing my device as applied thereto; Fig. 2 is a side 35 elevation of the same; Fig. 3 is a plan of the lever mechanism for operating the clutch with the foot; Fig. 4 is a sectional detail of the mechanism for holding the hand operating lever, being a section taken on 40 the line 4—4 of Fig. 1.

The side members of the press shown are designated 5 and 6 and are mounted upon a base 7 and support a cross member 8 extending across the top of the press and forming 45 an abutment for the head 9 of the ram 10. This ram 10 is adapted to be raised by mechanism, not shown, when the shaft 12 is rotated by the engagement of a clutch member 14 with the clutch member 15, rigid with a 50 driving pulley 16. The cross head 8 is shown as yieldingly held to the frame members 5 and 6 by means of springs 18 surrounding suitable studs and adjustably compressed by means of nuts 19 threaded onto the studs. 55 This is to prevent the breaking of any of the operating parts when too great a thick-

ness comes between the cross head 8 and the head 9.

The clutch member 14 in the press shown is adapted to be shifted by a bifurcated arm 60 of a bell crank 20 pivoted at 21, having its other leg 22 engaging an arm 23 of a foot lever 24 pivoted at 25 to the base 7 of the machine. When the foot lever 24 is depressed, the arm 22 is raised and the other 65 leg of the bell crank moves the clutch member 14 into engagement with the clutch member 15, thus starting the machine.

The foregoing is a brief description of a press with which my device may be used, 70 but it is to be understood that the same is simply illustrative of any suitable power machine. The attachment constituting my invention will now be fully described.

Rigidly secured to the members 26 forming a bifurcated portion of the bell crank 20 is a yoke 28 having thereon a transverse shoulder 29. Normally engaging this shoulder 29 are two latches 30 and 31 pivoted at 32 to a suitable bracket 33 carried on the 80 side member 6 of the machine. These latches are in the form of hooks, so shaped that either of them will prevent the movement of the clutch member 14 by reason of their engagement with the shoulder 29, except 85 when both are raised. To allow the shoulder to pass freely under the hooks on the return movement of the clutch member, they are beveled, as at 34, to present a cam surface to the shoulder. The return of this 90 clutch member is caused by the action of a tension spring 35 secured to the frame member 6 and to the bell crank member 20.

Suitably journaled in bearings 36 mounted on the sides of the frame members 5 and 6 are rock shafts 37 and 38. The rock shaft 38 has a rigid rock arm 40, to which is attached a chain 41 leading downwardly to the hook 30 to which it is suitably attached. A similar rock arm 43 is rigidly mounted 100 on the rock shaft 37 and is connected by a chain 44 to the other hook 31, the chain passing intermediately over a pulley 45 loose on the shaft 38. It results from this construction, that, when the rock shaft 38 is 105 turned to move the arm 40 upwardly, the latch connected to the chain 41 will be raised out of engagement with the shoulder 29, and, when the rock arm 43 is moved outwardly, by the rotation of the rock shaft 110 38, the other latch will be raised out of engagement with the shoulder 29 by means

of the chain 44. In order to rock these rock shafts to raise the hooks 30 and 31, and allow the clutch member to be thrown into action only when the operator's hands are 5 out of danger, I provide levers 48 rigidly carried on the forward end of these rock shafts 37 and 38. These levers extend toward the center of the machine adjacent the head 9 of the ram 10, but enough below 10 it, so that when the wrists or hands of the operator are depressing them by resting upon them, the hands will be entirely out of danger of getting between the head 9 and the cross head 8, where they could be 15 crushed. The inner ends of these levers 48 are preferably provided with suitable pads 49 to prevent discomfort when the hands are resting on them. Each lever 48 is adjustably carried by a block 50 rigidly secured to the 20 end of the respective rock shaft 37 or 38 and clamped thereon by means of an eye-bolt 51, through which the lever 48 passes. These eye-bolts, as shown, pass through the blocks 50 and act to draw the levers 48 down 25 against suitable ledges 53 under the influence of a thumb nut 54. This is to provide for lateral adjustment of these levers to accommodate different sized pieces of work to be operated upon by the machine.

30 In the operation of this machine, a portion of a box, indicated by broken lines at 56, is held by the operator around the head 9, and an end or other portion of the box is moved between the head 9 and the head 8. This 35 latter portion of the box having glue on its edges, is secured to the other portion of the box by the upward pressure of the head 9. Now, it will be seen that the operator's hands are down at the sides of the box portion being held by the hand, that the wrist 40 may depress the levers 48 by being in the position shown in Fig. 2. Thus the hooks controlling the movable clutch member may be raised only when both of these members 45 are depressed, insuring both hands being in a safe position.

Having thus described by invention, what I claim is:

1. The combination with mechanism liable 50 to injure the hands of the operator, of devices located adjacent said mechanism and adapted to control the starting thereof, said devices being adapted to be engaged by portions of the operator's arms while he is performing his regular work on the machine 55 and permitting the starting only when his hands are in safety position.

2. The combination, with mechanism liable 60 to injure the operator's hands, of a foot controlled clutch, a latch for preventing the movement of said clutch, and means con-

trolling said latch located a safe distance away from the dangerous mechanism and adapted to be moved by the operator's wrists when the hands are in working position to 65 permit the movement of said clutch and starting of the mechanism.

3. The combination, with a machine liable 70 to injure the operator, of a pair of rock shafts, means operated thereby for preventing the operation of the machine, and a pair of rods adjustably mounted on the rock shafts and projecting into the position for engagement by the wrists of the operator 75 while his hands are working but in safety position.

4. The combination, with a press having a movable head and an abutment block, of means for moving said movable head, a clutch for controlling said means, latches for 80 preventing the operation of the clutch, devices located adjacent to the movable head adapted to control said latches, connections between the latches and said devices, said devices being movable by the operator while 85 holding a blank to be operated upon to permit the movement of the clutch only when the operator's members are in safety position.

5. The combination, with a press having 90 an abutment block and a movable head, of means for controlling the movable head comprising a slideable clutch operated by a foot lever, latches controlling the movement of said clutch, rock shafts carried by the press, rock arms on the rock shafts, flexible connections between said latches and said rock shafts, and levers carried by the rock shaft extending to a point adjacent the movable head, whereby the rock shafts may be moved 95 to release the clutch when the operator's 100 hands are in safe position.

6. The combination, with a press having 105 an abutment-block and a movable head, of means for controlling the movable head comprising a slideable clutch operated by a foot lever, latches controlling the movement of said clutch, rock shafts carried by the press, connections between said latches and said rock shafts, and rods adjustably mounted in 110 clamps carried by the rock shafts and extending to points adjacent the movable head on each side thereof, whereby the rock shafts may be moved to release the clutch by the operator's forearms while his hands are at 115 work, provided his hands are in a safe position.

In testimony whereof, I hereunto affix my signature in the presence of two witnesses.

GEORGE HEAP.
